ADJUSTABLE TYPEWRITER SUPPORT

Wilbert E. Herman, Milwaukee, Wis.

Application September 4, 1934, Serial No. 742,653

2 Claims. (Cl. 312—29)

This invention relates to typewriter supports, and more particularly to a type of support that can be built into or made a part of a desk, and will support a typewriter at various heights from 5 the floor, making it more convenient for the user.

An object of my invention is to provide a separate unit that may be installed into a desk or table, adapted for its use, and so constructed as to permit a typewriter to be brought horizontally 10 to its operative position at will.

Another object of my invention is to provide an adjustable support for a typewriter that will permit changing the height of the table to suit the user's convenience.

Still another object of my invention is to provide a means that will conceal the typewriter, entirely, in a desk or table when not in use.

With the above and other objects which will be apparent as the description proceeds, the invention consists of the following novel features 20 and details of construction, to be hereinafter more fully described, illustrated in the accompanying drawings and pointed out in the appended claims.

In the accompanying drawings:

Fig. 1 is a fragmentary perspective view of the 25 mechanical unit showing the operative parts without the board support.

Fig. 2 shows another view of one of the side plates with a modified method of adjustment for 30 height.

Fig. 3 shows the board support on which the typewriter is fastened, equipped with rollers to allow ease in raising the typewriter to its operative level.

Fig. 4 shows a cross sectional plan view of the 35 device showing its operation.

Fig. 5 shows a front view of the device in position, and

Fig. 6 illustrates the entire assembly of the 40 device attached to a conventional type of open top desk.

Referring to the drawings in detail, wherein like characters of reference denote corresponding parts, the reference characters 10 and 11 indicate right and left hand vertical plates held in 45 position by the horizontal cross members 12, fastened to plates 10 and 11 at 18. There are channels 13, fastened in horizontal alignment to the inside of plates 10 and 11 and having similar 50 channels 14 and 21 with open ends 16 and 17 running in angular relation to the channel 13. The horizontal channels 15 fastened longitudinally to the outside of the plates 10 and 11, are held securely by means of screws in apertures 55 at 34. These apertures 34 through the plates 10

and 11, are in vertical relation to each other and permit the channel 15 to be placed at either one of several heights as shown.

The board support 19, supporting the typewriter 28, has rollers 24, 25 and 26 fastened to its sides, projecting outwardly from it. These rollers 24, 25 and 26 engage the channels 13 and allow horizontal movement of the board 19 in the channels 13. When the board 19 is forced back into the channel 13 the roller 24 enters the 10 opening 17 in the channel 21, at the same time that the roller 25 enters the opening 16, in the channel 14, allowing the entire board 19 to descend in the angular channels 14 and 21. This is illustrated at 22 and 23 in Fig. 4 showing the 15 descent of the board 19.

The entire unit with the channel 15 on the plates 10 and 11, as guides, engage the rails 27 fastened on the inside of the space provided in the desk 20.

In Fig. 2 a modified method of raising or lowering the entire unit is shown. The channels 29, supported by radial arms 30 and 31, hinged at 33, replace the channels 15. There are apertures 32 in radial alignment through the plates 10 and 11 25 and the arms 30 and 31 are secured by pins in these apertures 32.

In operation the door 36, concealing the entire unit in the desk 20, is opened, and the board 19 supporting the typewriter 28, is pulled out. This 30 will slide the entire unit on the rails 27, to a stop 37, and cause the rollers 24 and 25 to rotate in the channels 21 and 14, respectively, causing the board 19 to raise upward in a horizontal plane, when the rollers 24 and 25 reach the horizontal channel 13, the board 19, with the typewriter 28 attached, may be drawn out still further to a position most convenient to the operator. 35

If a variation in height is desired, the operator can make the necessary adjustment by changing 40 the pins or bolts in the apertures 34 or 32, in the plates 10 and 11, depending on the type or design, to raise or lower the entire device.

The invention is susceptible of various changes 45 in its form and minor details of construction, and the right is herein reserved to make such changes as properly fall within the scope of the appended claims.

Having thus described my invention, what I claim and desire to secure by Letters Patent in 50 the United States, is:

1. The combination with a support, of a carriage on said support and having vertical side plates and horizontal cross members supporting the same, angular channelled rails fixedly mount- 55

ed on the inner sides of said vertical side plates, horizontally disposed channel rails mounted for parallel movement by means of links on the outer sides of said vertical side plates, guide rails fixedly mounted on said support and engaged in the channels of the last named rails to allow for horizontal movements of said carriage, relative to said support and a mounting board having rollers engaged in the channels of the angular 5 channelled rails to allow for vertical and hori-

zontal movements thereof relative to said carriage.

2. The combination as set forth in claim 1, wherein the angular channelled rails are each formed to provide inclined portions to allow for the vertical movements of the mounting board and a horizontal portion to allow for the horizontal movement of the mounting board when the latter is disposed in its elevated position. 10
